US0D1090479S

(12) **United States Design Patent** (10) Patent No.: **US D1,090,479 S**
(45) Date of Patent: ** Aug. 26, 2025

(54) **ILLUMINATED LOUDSPEAKER**

(71) Applicant: **Harman International Industries, Incorporated**, Northridge, CA (US)

(72) Inventors: **Gianni Teruzzi**, Shenzhen (CN); **Ondrej Vaclavik**, Shenzhen (CN); **Zhilong Cheng**, Shenzhen (CN); **Mo Wang**, Shenzhen (CN); **Rongjian Huang**, Shenzhen (CN)

(73) Assignee: **Harman International Industries, Incorporated**, Northridge, CA (US)

(**) Term: **15 Years**

(21) Appl. No.: **29/879,918**

(22) Filed: **Jul. 14, 2023**

Related U.S. Application Data

(63) Continuation of application No. 29/867,245, filed on Oct. 17, 2022.

(51) **LOC (15) Cl.** **14-01**

(52) **U.S. Cl.**

USPC **D14/204**
